CLAIM

The ornamental design for a set of keys for a handset, as shown and described.

DESCRIPTION

FIG. 1 is a front view of a set of keys for a handset showing our new design;

FIG. 2 is a perspective front view thereof;

FIG. 3 is a front perspective of a second embodiment of a set of keys for a handset showing our new design; and,

FIG. 4 is a perspective front view thereof.

The broken line showing of environmental structure in the Figures for illustrative purposes only and forms no part of the claimed design.
